UNITED STATES PATENT OFFICE

158,563

BELT BUCKLE

John A. Doughtie, Jr., Kittredge, Colo.

Application May 17, 1948, Serial No. 146,417

Term of patent 7 years

(Cl. D17—1)

To all whom it may concern:

Be it known that I, John A. Doughtie, Jr., a citizen of the United States, residing at Kittredge, in the county of Jefferson and State of Colorado, have invented a new, original, and ornamental Design for a Belt Buckle, of which the following is a specification, reference being had to the accompanying drawing, forming part thereof.

Figure 1 is a top plan view of a belt buckle, showing my new design.

Figure 2 is an underside plan view thereof.

Figure 3 is a longitudinal edge view, and

Figure 4 is an end view of the same.

I claim:

The ornamental design for a belt buckle, as shown.

JOHN A. DOUGHTIE, JR.
